(57) **CLAIM**

The ornamental design for a computer generated image for a display panel or screen, as shown and described.

DESCRIPTION

FIG. 1 is a front view of a computer generated image for a display panel or screen showing a first embodiment of our new design; and,

FIG. 2 is a front view of a second embodiment thereof.

The broken lines in the FIGS. are directed to environment and are for illustrative purposes only. The broken lines form no part of the claimed design.

1 Claim, 2 Drawing Sheets

FIG. 1

FIG. 2
